UNITED STATES PATENT OFFICE.

WILLIAM EHRLICH, OF CHICAGO, ILLINOIS, ASSIGNOR TO CASE & MARTIN COMPANY,
OF CHICAGO, ILLINOIS, A CORPORATION OF ILLINOIS.

PIE-MAKING MACHINE.

1,397,272.

Specification of Letters Patent. Patented Nov. 15, 1921.

Application filed September 29, 1919. Serial No. 327,252.

To all whom it may concern:

Be it known that I, WILLIAM EHRLICH, a citizen of the United States, residing at Chicago, in the county of Cook and State of Illinois, have invented certain new and useful Improvements in Pie-Making Machines, of which the following is a specification.

My invention relates to pie-making machines and has for one of its objects the provision of simple and efficient means for crimping and sealing the crusts of pies.

A further object is the provision of a crimping machine for pie-making machines in which the device moves along with the pies while the crimper is in engagement with the pies so as to prevent tearing such pies.

Another object is the provision of a crimping device for pie-making machines which can be thrown out of gear only at a predetermined position in its cycle of movement and which can only be thrown into operative condition when in a predetermined position of its movement and all in timed relation to the movement of pies adjacent the crimping device.

A still further object is the provision of providing means for preventing scraps of pies and other foreign material from getting into the conveyer part of the apparatus.

Other objects will appear hereinafter.

An embodiment of my invention is illustrated in the accompanying drawings, forming a part of this specification, and in which—

Figure 1 is a plan view embodying my invention;

Fig. 2 is a vertical cross-section taken on line 2—2 of Fig. 1;

Fig. 3 is a side elevation of a fragment of the device; and

Figs. 4 and 5 are views similar to Fig. 3, except showing the parts in different positions.

Referring more particularly to the drawings I have indicated an end portion only of a pie machine which is of the class for completely forming pies. In this device a conveyer 10 is mounted on tracks 11 and the latter supported on a frame 12. The conveyer 10 is driven in any desirable manner, not shown.

In devices of this character the conveyer

10 is an endless conveyer and travels substantially horizontally. Adjacent one end of the device is a cutting bar 13 and a cutting wheel 13' positioned so that as the pies travel around the end of the conveyer the upper and lower crusts are trimmed off against the edge of the pie tin by the parts 13 and 13' pressing against the pie tin, thereby severing the protruding edges of the pie crusts.

Attached to the conveyer 10 is a plurality of members 14 which have sliding surfaces 15 engaging the tracks 11 to support the conveyer 10. These members 14 have vertical openings therein providing bearings for upright spindles 16, and on the upper ends of said spindles are mounted hubs 17 carrying pie holders 18 at their tops. The members 14 are preferably spaced apart at substantially equal distances on the conveyer 10.

Immediately above the parts 14 and resting thereon I provide a plurality of plates 19 which are disposed in overlapping condition, as clearly indicated. The ends of each plate 19 are rounded and one end of each plate provided with a slot 20 and the other end provided with a substantially circular opening 21. The openings 20 and 21 are disposed about the spindles or shafts 16 so as to hold the plates 19 in position. It will be apparent that the slots 20 provide means for the plates 19 being moved slightly longitudinally of each other when passing around with the conveyer 10. The slots 20 also facilitate the attachment and removal of the plates 19. These plates 19 are of sufficient width to prevent the pie crusts and other foreign material from falling down onto the tracks 11 and conveyer 10.

Secured to a part of the frame 12 is an upright frame 23 near one end of the machine, as clearly indicated in Fig. 1. In this frame 23 is an upright shaft 24 having a connection with the conveyer 10 so that one complete rotation of shaft 24 takes place while the conveyer moves a distance equal to the distance between two of the members 14. Any suitable driving connection may be used as desired. I have indicated a suitable connection comprising a sprocket 24' on shaft 24 and a sprocket 24'' on the shaft of cutting wheel 13' with a sprocket chain 25' con-

necting sprockets 24' and 24''. Horizontally mounted in the frame 23 is a shaft 25 and connected with the shaft 24 by bevel gears 26. The shaft 25 is preferably provided with a friction brake 27 so that when the crimping mechanism, described later, is thrown out of motion, shaft 25 will stop immediately. Any form of friction brake 27 may be used.

10 When the machine is used for merely trimming pies having no top crusts, the crimping mechanism is disengaged from the driving means by a manually operated clutch. A suitable form of clutch is indicated by a member 28 splined on shaft 25 with a projection 29 adapted to engage a notch 30 in the hub of the gear 26 on shaft 25. The splined part 28 is also provided with a projection 31 adapted to engage a notch 32 in a bearing 33 of the shaft 25. The splined part 28 has a groove 34 engaged by a lever 35 which is pivoted as at 36. A lever 37 is pivoted as at 38 and has a spring 39 mounted on a rod 40, and the latter pivoted as at 41 to the lever 37. The rod 40 is slidably mounted in a head 42 which is pivoted in the end of lever 35 and spring 39 presses against said head 42 to cause movement of the lever 35. Stops 43 and 44 are provided to limit the oscillatory movements of lever 37. The arrangement is such that spring 39 tends to press the lever 35 in one direction when lever 37 is engaging stop 44 and when lever 37 is swung on its pivot 38 to its dotted line position in Fig. 1 it rests against stop 43 and tends to press lever 35 in the opposite direction. When lever 37 is engaging stop 44 spring 39 tends to hold projection 31 in the notch 32 of bearing 33, and when lever 37 is engaging stop 43 lever 35 tends to hold projection 29 in notch 30 of the hub of gear 26. The space between hub of gear 26 and bearing 33 is such that member 28 and one of the projections 29 or 31 can just rotate between said bearing 33 and hub of gear 26. With this arrangement when member 28 is pressed toward bearing 33 projection 31 will ride against the end of bearing 33 until it engages notch 32 when it will enter said notch and stop rotation of shaft 25. When member 28 is pressed toward gear 26 projection 29 will ride against the end of gear 26 until it engages notch 30 when it will move into said notch and cause member 28 to rotate shaft 25. With this arrangement when shaft 25 is at rest and it is desired to throw it into motion lever 37 is moved to its dotted line position in Fig. 1. This causes member 28 to engage notch 30 to rotate the shaft.

60 To disconnect the shaft 25 from the driving shaft 24, the lever 37 is moved to shift the splined member 28 out of engagement with the notch 30 into engagement with the notch 32 of the bearing 33. This stops the shaft 25 and the crimping mechanism is so

positioned with relation to shaft 25 that it will be out of the path of movement of a pie in pie holder 18.

At the upper end of frame 23 is a guide 45 in which is mounted a block 46 and adapted for vertical movement. Attached to the block 46 is a horizontal bar 47 and pivoted to and depending from said bar are a plurality of links 48. The lower ends of links 48 are pivoted to arms 49 which are attached to a crimper head 50. The arrangement is such that during all of the movements of crimper head 50 it remains in parallel relation with the bar 47, and hence horizontally, so that it is substantially parallel with the upper surface of a pie in the pie holder 18. The shaft 25 carries a crank pin 51 which is connected with a yoke 52, and the latter pivoted as at 53 to the links 48. Secured to the shaft 25 and rotatable therewith is a crank-pin wheel 51.1 which is interposed between the yoke 52 and shaft 25. The crank pin wheel may be provided with a plurality of openings each at a different distance from the axis of shaft 25, see Fig. 3, for receiving the crank pin 51 so as to vary the throw of the latter to adjust the movements of the crimping head 50. This provides means for moving the crimper head 50 in a circular path and along with the pie holder during the crimping operation. One of the links 48 is provided with an arm 54, and pivoted to the arm 54 is a link 55. The link 55 is pivoted to the middle part of a bar 56 at its lower end and the bar 56 pivoted to shanks 57 of stripping members 58 and 58'. The shanks 57 are slidably mounted in upright openings in ears 59 on the crimper head 50. A spring 60 is connected to one end of bar 56 and the arm 54 so that the stripper 58' is rocked downwardly below the surface of the crimper head 50, as clearly indicated in Figs. 3, 4 and 5. Also, connected with link 55 is a spring 61 which is mounted in such a manner as to take most of the weight of crimper head 50 and its mounting from the crank pin 51 so as to facilitate easy and smooth movement of the crimper head in action. The link 55 is provided with a slot 62 so as to permit its movement on a pin 63 in the end of arm 54. As the crimper 50 engages pie A, stripper 58' engages the pie before stripper 58 causing spring 60 to lengthen and the link 55 to slip upwardly with the slot 62 sliding on pin 63. Then as the crimper 50 is lifted from the pie, stripper 58 is lifted from the latter before stripper 58' because of spring 60 and its manner of being mounted. In Fig. 3 the crimping mechanism is shown in its position of rest. It will not matter when lever 37 is operated to throw the crimping mechanism into and out of operative position. This mechanism will not be operative until the parts have reached their position shown in Fig. 3 either 130

in throwing the crimping mechanism into or out of operative condition. In Fig. 4 the crimping mechanism is shown in position with the crimping head 50 engaging a pie A 5 in the pie holder 18. In Fig. 5 the parts are shown with the crimping head 50 just leaving the pie and the strippers 58 and 58' disengaging the pie and crimper head 50. Without these strippers the dough of the 10 crusts tends to stick to the crimper and tends to pull the pie out of the pie holder or else tear the crusts. The spring 60 tends to hold the stripper 58' at the rear side of the pie in engagement with the pie longer than the 15 other stripper. This facilitates clearing the crimper head from the pie as the side of the crimper head adjacent stripper 58' tends to stick to the pie longer than the other side in use.

20 Adjacent the pie-crimping mechanism on the frame 12 I provide a resiliently mounted track section 64 which is pivoted as at 65 on a member 66. The member 66 is provided with a slot 67 and member 64 provided with 25 a bolt 68 mounted in the slot. Mounted in frame 66 is a screw 69 having a restricted portion with a spring 70 mounted in this portion and pressing upwardly on track 64. Each of the members 14 is provided with a 30 roller 71 which is adapted to engage the track. With the resilient support under one end of track 64 this tends to press the pie holder 18 up against the crimping head while a pie is being crimped, giving a resilient pressure between the pie holder and crimping head.

Although but one specific embodiment of this invention has been herein shown and described it will be understood that numerous details of the construction shown may be altered or omitted without departing from the spirit of this invention as defined by the following claims.

I claim:—

45 1. A pie machine comprising a carriage, a pie holder on said carriage, a crimping head, a mounting carrying said crimping head, and means for moving said mounting to shift said head into engagement with a pie 50 on said holder, said means being also arranged to shift said head in the direction of movement of said holder.

55 2. A pie machine comprising a carriage; a pie holder on the carriage adapted for movement along a predetermined path; and a pie crimping head mounted for movement in a circle toward and away from the path of said pie holder with the latter and the pie crimping head moving along together 60 when adjacent each other.

65 3. A pie machine comprising a carriage; a plurality of evenly spaced pie holders on the carriage adapted to move along in a path; a pie crimping head mounted for movement in a circular path, the pie crimp-

ing head and pie holders being timed to move so that the pie crimping head makes one complete rotation while the pie holders are moving a distance equal to the distance between two of such pie holders.

70 4. A pie machine comprising a carriage; a pie holder on the carriage adapted for movement along a predetermined path; a guide disposed at substantially right angles to the path of the pie holder; a pie crimping head between the guide and path of the pie holder; a mounting attached to the pie crimping head and having a portion slidably mounted on said guide; and a crank attached to the mounting adapted to guide the 75 pie crimping head in a circular movement toward and away from the path of the pie holder.

80 5. A pie machine comprising a pie holder mounted for movement along a substantially straight path; and a crimping head mounted for movement in a circular path, said paths being disposed so that the crimping head and pie holder approach each other at points 85 in their paths.

90 6. A pie machine comprising a pie holder mounted for movement along a predetermined path; a guide disposed substantially at right angles to the path of the pie holder; a bar slidably mounted on the guide; a pie crimpler; two substantially parallel links connecting the bar with the pie crimpler and holding the latter substantially parallel with said bar; a bar connecting said links; and a crank attached to the last-mentioned bar. 100

95 7. A pie machine comprising means for moving a pie along a substantially horizontal path; a pie crimping head mounted for movement in a circular path with a point in the path of the pie holder adjacent the 105 path of the crimping head; and means maintaining the crimping head with its pie-engaging surface substantially parallel with a pie in the pie holder.

110 8. A pie machine comprising a plurality of spaced pie holders mounted for movement along one path; a pie crimpler; a crank; a guideway; a mounting attached to the guideway and crank and supporting the pie crimpler, the latter being adapted to 115 move in a circular path toward and away from the path of the pie holders; and an operative connection between the pie holders and pie crimpler moving the pie crimpler into 120 operative relation successively with the pie holders.

125 9. A pie machine comprising a bar slidably mounted; two links pivoted to the bar; a pie crimping head connected to said bar; and a power driven crank connected with the bar for moving the pie crimping head in a circle and slide the bar on its mounting.

130 10. A pie machine comprising a pie crimping head; a bar slidably mounted; two links connecting and holding in parallel relation

- the bar and pie crimping head; and a crank connected with said links giving rotary motion to the pie crimping head and sliding movement to the bar.
5. 11. A pie machine comprising a pie crimping head; a bar slidably mounted; two links connecting and holding in parallel relation the bar and pie crimping head; a crank connected with said links giving rotary motion to the pie crimping head; a plurality of pie holders spaced apart; a mounting for the pie holders; and a connection between the pie holder mounting and said crank adapted to move the crank through one turn while said mounting is moving a distance equal to that between two pie holders.
10. 12. A pie machine comprising a pie crimping head; a bar slidably mounted; two links connecting and holding in parallel relation the bar and pie crimping head; means for imparting motion to the aforesaid parts; and a spring partially supporting the crimping head, bar and links.
15. 13. A pie machine comprising a conveyer; a plurality of pie holders on the conveyer; an upright support having guides above the conveyer; a bar slidably mounted in said guides; a plurality of links pivoted to and depending from the bar; a crimping head pivoted to the lower ends of said links; a crank connected with said links; and an operative connection between the crank and conveyer in timed relation to bring the crimping head down close to each pie holder as the latter pass under said crimping head.
20. 14. A pie machine comprising a conveyer; a plurality of pie holders on the conveyer; an upright support having guides above the conveyer; a bar slidably mounted in said guides; a plurality of links pivoted to and depending from the bar; a crimping head pivoted to the lower ends of said links; a crank connected with said links; an operative connection between the crank and conveyer in timed relation to bring the crimping head down close to each pie holder as the latter pass under said crimping head; and a stripper associated with the crimping head for stripping pies from the latter.
25. 15. A pie machine comprising a pie crimping head; a plurality of links supporting the crimping head; an arm on one of said links; a link depended from said arm; a bar pivoted at its central part to the last-mentioned link; a spring connected to one end of said bar; and a stripper having a shank pivoted to each end of the bar, said shanks being slidably mounted at opposite edges of the crimping head.
30. 16. A pie machine comprising a crimping head; a shaft operatively connected with the crimping head; a conveyer; a pie holder on the conveyer; a clutch consisting of three parts, one part being operatively connected with the conveyer and having a notch therein, another part being a fixed member adjacent said shaft and having a notch therein, and the other part being splined on said shaft between the two first-mentioned parts; projections on the splined part of said clutch adapted to engage said notches, one at a time; and means for controlling movements of said splined part.
35. 17. A pie machine comprising a conveyer; a pie holder on the conveyer; a crimping head mounted to travel in a circle toward and away from the path of said pie holder; and means for stopping the movement of the crimping head in a predetermined position of its movement.
40. 18. A pie machine comprising a conveyer; a pie holder on the conveyer; a pie crimper mounted above the conveyer and adapted for movement toward the pie holder to crimp a pie in the latter; and a resiliently mounted track adapted to support the pie holder while the crimping head is engaging a pie in the pie holder.
45. 19. A pie machine comprising a conveyer; a pie holder on the conveyer; a pie crimper mounted above the conveyer and adapted for movement in a circle toward and away from the pie holder to crimp a pie in the latter; and resilient means tending to press the pie holder toward the crimping head during the crimping operation.
50. 20. In a pie machine, the combination of a frame, a conveyer continuously movable along said frame, pie-plate supports carried by said conveyer, a standard mounted on said frame, a member mounted on said standard and shiftable vertically and horizontally, and means carried by said member and movable thereby into contact with the dough on pie plates resting on said supports so that during the travel of said pie plates adjacent to said standard, the dough around the perimeter of the pie plates is properly shaped.
55. 21. In a pie machine, the combination of a frame, a conveyer continuously movable along said frame, pie-plate supports carried by said conveyer, a standard mounted on said frame, a member mounted on said standard and shiftable vertically and horizontally, and an annular element carried by said member and movable thereby into contact with the dough on pie plates resting on said supports so that during the travel of said pie plates adjacent to said standard, the dough around the perimeter of the pie plates is properly shaped.
60. 22. In a pie machine, the combination of a frame, a conveyer continuously movable along said frame, pie plate supports carried by said conveyer, a standard mounted on said frame, a member mounted on said standard and shiftable vertically and horizontally,

tally, means carried by said member and movable thereby into contact with the dough on pie plates resting on said supports so that during the travel of said pie plates adjacent to said standard, the dough around the perimeter of the pie plates is properly shaped, and a stripper carried by said member and movable relatively of said shaping

means, said stripper comprising relatively movable parts successively shiftable out of engagement with a pie carried on the adjacent support.

In testimony whereof I have signed my name to this specification on this 25th day of September, A. D. 1919.

WILLIAM EHRLICH.
